UNITED STATES PATENT OFFICE.

LAWRENCE E. JOHNSON, OF WINTHROP, AND EDWARD ERICKSON, OF LYNN, MASSACHUSETTS, ASSIGNEES TO VICTOR SHOE MACHINERY CO., OF BOSTON, MASSACHUSETTS, A CORPORATION OF MASSACHUSETTS.

AWL-FEEDING MECHANISM FOR SEWING-MACHINES.

1,133,150.

Specification of Letters Patent. Patented Mar. 23, 1915.

Original application filed May 19, 1913, Serial No. 768,671. Divided and this application filed November 14, 1913. Serial No. 801,278.

To all whom it may concern:

Be it known that we, LAWRENCE E. JOHNSON, a citizen of the United States of America, and a resident of Winthrop, in the 5 county of Suffolk and State of Massachusetts, and EDWARD ERICKSON, a subject of the King of Sweden, and a resident of Lynn, in the county of Essex and State of Massachusetts, have invented certain new and useful 10 improvements in Awl-Feeding Mechanisms for Sewing-Machines, of which the following is a specification.

This invention relates to awl feeding mechanisms for shoe sewing machines and 15 has for its object the production of a movable frame supporting the awl and needle in the same vertical plane, so that the entering of the needle into the hole in the work formed by the awl is always secured, 20 vision also being made to move said frame while the awl is in the work, thus feeding the work relatively to the work support.

Another object of said invention is to provide means for regulating the length of feed 25 while the machine is in operation.

The invention consists in certain novel features of construction and arrangement of parts which will be fully understood by reference to the description of the drawings and to the claims hereinafter given.

Of the drawings: Figure 1 represents a plan of a sewing machine embodying the principles of the present invention. Fig. 2 represents a front elevation of the same. Fig. 3 represents an elevation of the right hand end of same. Fig. 4 represents a vertical section of the same looking to the right, the cutting plane being on line 4—4 on Fig. 1. Fig. 5 represents a vertical section of 35 the same, looking to the left, the cutting plane being on line 5—5 on Fig. 1. Fig. 6 represents a sectional detail, the cutting plane being on line 6—6 on Fig. 3. Fig. 7 represents an elevation of the needle and awl driving members and showing the looper hook and the cam for operating it, and Fig. 8 represents an elevation of the left end of 40 machine.

Similar characters designate like parts 50 throughout the several figures of the drawings.

In the drawings, 20 is the base of the machine adapted to be secured to a column and having the end frames 21 and 22 provided with bearings for the revoluble shaft 23.

55

The revoluble shaft 23 has the driving wheel 24 secured to one end thereof while to its opposite end is keyed the cam disk 25. Interposed between the side frames 21 and 22 and keyed to the shaft 23 are the cam disks 26 and 27. The cam disks 25—26—27 are adapted to operate the various mechanisms necessary for the proper operation of the machine, all of which have been fully illustrated and described in another applications of ours filed May 19, 1913, and numbered 768,671. Inasmuch as these mechanisms form no part of the present invention they are described only so far as they relate to the awl feeding and needle operating mechanisms to which the present invention is confined. To the inner side of the side frame 21 is secured the work support 28 which may be of any well-known construction. The side frame 21 has also 70 formed upon its inner face a race 30 for the shuttle 31 which is driven in any well-known manner.

The shuttle 31 is provided with a cap 41 pivoted at 42 to the side frame 21, said cap 80 being adapted to be moved about its pivot to permit the removal of the shuttle 31 when it is desired to renew the bobbin.

The frame 22 has rigidly mounted thereon two parallel studs or pins 60, 61, on which 85 is mounted a movable frame 62. This frame has pivoted to the lower end thereof at 63 an oscillating slotted lever 64 the lower end of which is provided with a roller 65 extending into a cam path 66 in the periphery 90 of the cam disk 27.

In the slot 67 of the lever 64 is a fulcrum block 68 pivotally mounted in a forked member 69 having a shank 70 extending through a straight slot 71 in the frame 22 95 and also through a slot 72 in a hand lever 73 pivoted at 74 to the end frame 22. That portion of the shank that travels in the slot 71 is flattened to fit said slot and be guided thereby. The shank 70 is surrounded by 100 washers 75 between which is a spring 55 tending to retain the lever 73 against the

flange around the slot 71, the friction thereon being sufficient to hold the lever 73 in adjusted position. The washers 75 and spring 55 are retained in position by means 5 of the nut 76. It is obvious that when the cam disk 27 rotates, the cam path 66 thereof will operate upon the roller 65 to actuate the lever 64 about its fulcrum thereby moving the frame 62 a given distance, 10 this distance depending upon the position of the fulcrum pin 77. The inclination of the slot 71 conforms to that of the lever 64 to permit the free movement of the forked member 69 lengthwise of the lever 64 without binding thereon.

By means of the handle 73 the position of the fulcrum block 68 may be changed at will to secure any desired degree of feed. It is obvious that the shank 70 will be moved 20 in the slot 71 during the movement of the hand lever 73 about its pivot 74, and when adjusted the friction on the lever will be sufficient to retain it in this position. When desired the nut 76 may be adjusted so that 25 the lever 73 will be immovably clamped against the wall of the side frame 22 and thereby positively locked so that a continuously uniform feed of the work will be obtained. The frame 62 has a long bearing 30 formed therein in which is mounted the shaft 80 having pinned to its outer end a collar 81 provided with an ear 81* between which and a pin on the upper end of the frame 62 is interposed a spring 82 adapted normally 35 to retain the needle guide 83 secured to the opposite end of the shaft 80 in proper relative position to the needle 84 carried by the needle support 85. The guide 83 is normally positioned by the pin 833 in the hub 40 thereof bearing against a wall of said needle support 85, said pin being retained in this contacting position by the spring 82. The needle guide 83 is provided with a slot 83* at its outer end which retains the oil therein 45 and serves as a means for lubricating the needle as it moves through said guide in either direction. When the needle 84 is operating the guide 83 is adapted to move with the needle support 85 until the ear 81* 50 on the collar 81 comes into contact with the pin 811, when further movement of the guide 83 will be prevented.

The needle support 85 has a gear segment 55 formed thereon and is provided with a tubular sleeve 86* surrounding the shaft 80 in the long bearing in the frame 62 and about the axis of which it is adapted to be oscillated by the lever 87 having formed thereon at one end a gear segment 88 meshing 60 with the gear segment 86. The teeth of the gear segment 88 are of sufficient length to permit the teeth of the gear segment 86 to remain constantly in mesh during the movement of the frame 62 in either direction. The lever 87 is pivoted at 89 to the

frame 21 and is provided at its rear end with a roller 90 in the cam path 91 formed in the cam disk 26. During the rotation of the disk 26 the cam path 91 operates upon the roller 90 to give the required movement 70 to the needle segment at the proper time. The needle support 85 has also secured thereto to the awl 911 positioned thereon so as to enter a slot in the work support 28 and the work supported thereby during a portion of the oscillation of said needle support, this awl being in the same vertical plane with the needle 84.

The lever 87 is provided on one side with a cam extension 92 adapted to act upon a roller 93 on a bell crank lever 94 pivoted at 95 to the side frame 21 beneath the shuttle race 30. The forward end of the lever 94 has secured therein a looper hook 96 and a spring 97 is provided to retain the roller 8* 93 in contact with the cam extension 92 at all times.

The lever 87 is provided with an upwardly extending arm 98 to the upper end of which is pivoted a link 99 the opposite end of 90 which is articulated to a loop spreader 100 pivoted at 101 to the hub 102 formed on the upper end of the movable frame 62.

The forward end of the spreader 100 is curved downwardly and rearwardly as indicated in Fig. 5 and its left hand edge is inclined as shown in Fig. 2. This mechanism provides a simple means for spreading the loop of thread at the proper time for the hook of the shuttle 31 to enter the same.

The loop spreader 100 operates in the same plane with the hook of the shuttle 31 and when the barb of the needle 84 has drawn the loop of thread through the work the 105 tapered end of said spreader will enter between the two portions of the thread on said barb and spread them apart so that the shuttle-hook will be sure to enter.

When the needle 84 has passed through 110 the work so that its barbed end extends below the work support 28 the looper hook 96 will also be moved downwardly so that when the looper 120* operates the thread 125 will not only be placed upon the barb of the needle 84 but it will also be carried around the hook 96 so that a given amount of thread will be always measured off to be carried through the work by the needle 84 preparatory to its coacting with the shuttle 120 in the formation of the stitch.

As has been stated, the needle 84 and the awl 911 are in the same vertical plane and oscillate about the same axis so that the entering of the needle 84 into the hole in the 125 work formed by the awl is always assured and no opportunity is afforded for them to get out of register.

The needle and awl support 85 is mounted on the movable frame 62 and when the awl 130

is in the work the latter may be fed relative to the work support, the length of feed being determined by the handle 78, it being obvious that by means of the devices controlled by said handle a change in the feed may be obtained at any time while the machine is running. When the needle leaves the work the frame 62 is returned to its normal position before the awl again moves forward to pierce the work.

It will be seen that by the construction shown and described, a very compact awl feeding and needle operating mechanism for sewing machines is provided in which the parts are reduced to a minimum.

The machine is particularly adapted to be used by unskilled labor such as shoe repairers, although it may be used equally as well on new work.

It is believed that the operation and many advantages of this invention will be fully understood from the foregoing description.

Having thus described our invention, we claim:

1. In a shoe-sewing machine, the combination of an oscillating support provided with a tubular shank formed thereon and revoluble therewith in a fixed bearing; a needle and awl secured to said support and adapted to alternately pierce the work; a shaft extending through said tubular shank; a disk on one end of said shaft provided with a needle guide and having a member normally engaging said support; a member secured to and radiating from the opposite end of said shaft; a fixed stop in the path of said radiating member; and a spring co-acting with said radiating member to move said shaft about its axis.

2. In a shoe-sewing machine, the combination of an oscillating support provided with a tubular shank formed thereon and revoluble therewith in a fixed bearing; a needle and an awl secured to said support in the same vertical plane and adapted to alternately pierce the work; a needle guide provided with a shaft rigidly secured thereto extending through said tubular shank and adapted to be oscillated therein; a pin on the needle guide normally engaging said support; a spring controlled member secured to the opposite end of said shaft; and a stop to limit the movement of said member about the axis of said shaft.

3. In a shoe-sewing machine, the combination of a frame having guide members thereon movable in the frame of the machine and supporting the needle and awl mechanisms; a fixed work support; a slotted lever pivoted to said movable frame; a roller in the opposite end of said lever; a cam for said roller; a fulcrum member in the slot of said lever; a bifurcated member straddling said lever and to which said fulcrum member is pivoted, said bifurcated

member being provided with a shank extending through a slot in a side frame; and a pivoted handle connected to said shank.

4. In a shoe-sewing machine, the combination of a frame having guide members thereon movable in the frame of the machine and supporting the needle and awl mechanisms; a fixed work support; a slotted lever pivoted to said movable frame; a roller in the opposite end of said lever; a cam for said roller; a fulcrum member in the slot of said lever; a bifurcated member straddling said lever and to which said fulcrum member is pivoted, said bifurcated member being provided with a shank extending through a slot in a side frame; a pivoted handle provided with a slot through which said shank extends; a spring surrounding said shank outside of said lever; and a nut on the outer end of said shank.

5. In a shoe-sewing machine, the combination of a fixed frame having a straight slot therein; a movable frame thereon supporting the needle and awl mechanisms and provided with two parallel pins reciprocable in said fixed frame; a fixed work support; a slotted lever pivoted at one end to the machine frame and at the other end to said movable frame, said lever being in the same plane with said straight slot; a roller in the opposite end of said lever; a cam for said roller; a block slidable in said lever slot; a fulcrum pin extending therethrough, a bifurcated member straddling said lever and having said fulcrum pin fixed therein; a shank thereon extending through said straight slot; an operating handle pivoted to the frame of the machine and through which said shank extends; and means on said shank for retaining said pivoted lever in adjusted position.

6. In a shoe-sewing machine, the combination of a movable frame having two parallel guide members reciprocable in the framework of the machine and provided with a cylindrical hole parallel with said guide members; a needle and awl support provided with a tubular shank positioned in said cylindrical hole; a needle guide provided with a stud positioned in said tubular shank; means for limiting the movement of said needle guide including in part a disk secured to the outer end of said stud; means for oscillating said needle and awl support; a work support; and means for moving said frame laterally relative to said work support.

7. In a shoe-sewing machine, the combination of a movable frame having two parallel guide members reciprocable in the framework of the machine and provided with a cylindrical hole parallel with said guide members; a needle and awl support provided with a tubular shank positioned in said cylindrical hole; a needle guide pro-

vided with a stud positioned in said tubular shank; means for limiting the movement of said needle guide including in part a disk secured to the outer end of said stud; means for oscillating said needle and awl support; a loop spreader pivotally mounted on said frame and movable laterally therewith; cam mechanism for operating said loop spreader at a predetermined time; a work support;

and means for moving said frame laterally to relative to said work support.

Signed by us at Boston, Mass., this 22nd day of October, 1913.

LAWRENCE E. JOHNSON.
EDWARD ERICKSON.
